UNITED STATES PATENT OFFICE.

BARTON W. SCOTT, OF SAN JOSE, CALIFORNIA.

PROPELLER.

1,024,032.

Specification of Letters Patent. Patented Apr. 23, 1912.

Application filed April 24, 1911. Serial No. 622,883.

To all whom it may concern:

Be it known that I, BARTON W. SCOTT, a citizen of the United States, residing at San Jose, in the county of Santa Clara and State 5 of California, have invented certain new and useful Improvements in Propellers; and I do declare the following to be a full, clear, and exact description of the invention, such as will enable others skilled in the art to 10 which it appertains to make and use the same.

This invention relates to propellers, and the object of the same is to construct each blade with the largest possible working surface 15 and to so shape its rear edge that the water delivered therefrom will be thrown straight back on lines parallel with the axis, rather than being directed either inward toward or outward away from such axis which would 20 set up currents directed toward the volume of water in rear of the propeller that it would have to overcome without a corresponding resultant forward impulse. Broadly speaking this object is accomplished by constructing each blade of the propeller with practically two thirds or perhaps three quarters of its body flat from its front edge or corner backward, and giving its rear edge or corner a slight curl or curve 25 forward in the direction of rotation, and specifically the curls or curves of the various blades are struck around lines which converge slowly toward the axis and would reach it (if projected) at a point far in rear 30 of the propeller. The specific construction is more fully set out in the following specification and shown in the drawings wherein—

Figure 1 is a side view of a propeller constructed in accordance with my invention. Fig. 2 is a front end view thereof. Fig. 3 is a rear end view. Fig. 4 is a vertical cross section on the line 4—4 of Fig. 1. Fig. 5 is a similar view on the line 5—5 of Fig. 1. Fig. 6 is a similar view on the line 6—6 of Fig. 1. Fig. 7 is a detail perspective view of one of the blades.

Referring more particularly to the drawings 1 denotes the shaft and 2 the hub of my improved propeller. On the hub 2 and preferably formed integral therewith is a series of radially projecting propeller blades 3, three of which are preferably provided.

The contour of each blade as viewed in plan is immaterial to the gist of the present invention, but by preference it is substantially triangular, with one corner united to

the hub 2 a second corner 5 standing somewhat forward of the same, and the third corner 4 somewhat in rear of the hub and by preference further remote from the axis than the front corner 5. As a whole the blade is disposed obliquely to the axis of the shaft 1, the degree of its angle thereto depending upon the purposes for which the propeller is to be used, the speed of its rotation, the weight to be driven, the size, of parts, and other conditions which will not enter into the present invention. The major portion of each blade (two-thirds or perhaps three-quarters thereof) is substantially flat with no or at least very little spiral so that what might be called the working surface of each blade bears steadily on the water which it cleaves and presses with equal force thereon throughout most of its area. This flat portion of the blade I have designated by the numeral 6. But the gist of my idea lies in the fact that the outer and rear corner of the triangular blade are curled or curved slightly inward in the direction of rotation of the propeller, so that the water which the blade is cleaving will be here to an extent trapped or cupped by the blade toward the rear edge of its working surface; and I have found by experience that when the line around which this curve is struck is one that converges slowly toward the axis and will reach it at a point far in rear of the propeller, rather than being one which is parallel with the axis or which diverges therefrom to the rear, the result will be that the centrifugal action of the water as it leaves the propeller is overcome to a great extent or rather is converted into motion in a direction strictly to the rear and parallel with the shaft 1. Obviously, whatever construction of the propeller is adopted which results in forcing water away from it on lines strictly parallel with the direction in which the propeller itself is progressing forward, the result will be the greatest efficiency of such propeller as a means for driving itself through the water; and with this object in view I may add that the greatest efficiency of the structure above described perhaps lies in the exact degree of curvature and angle of convergence at the points designated by the numerals 7, although consideration must be given to the conditions and other collaterals as suggested above.

From the foregoing description taken in connection with the accompanying draw-

ings, the construction and operation of the invention will be readily understood without requiring a more extended explanation.

Various changes in the form, proportion and minor details of construction may be resorted to without departing from the spirit or sacrificing any of the advantages of the invention as defined in the appended claim.

What is claimed is:

10. The herein described propeller having its hub mounted on an axle, and a series of blades whereof each is substantially triangular in plan with one corner connected to said hub and the other corners disposed forward and rearward thereof, the major portion of the body of the blade being disposed oblique

to the shaft and substantially flat throughout and the rear corner thereof being curved forward in the direction of rotation around a line which is projected would meet the projected axis at a point far in rear of the propeller, the degree of curvature and the angle of convergence being such that the water will be forced away from said propeller on lines strictly parallel with its axis. 20 25

In testimony whereof I have hereunto set my hand in presence of two subscribing witnesses.

BARTON W. SCOTT.
